HIGH FREQUENCY CIRCUITS

Frederick A. Kolster, New York, N. Y., assignor to
 Federal Telegraph Company, Newark, N. J., a
 corporation of California

Application October 12, 1932, Serial No. 637,564

21 Claims. (Cl. 250—40)

This invention relates to high frequency circuits, and particularly to circuits for use in connection with vacuum tubes designed to operate in the high frequency region of the radio spectrum.

An object of the invention is to provide a device for use in a high frequency oscillator circuit which will increase the frequency stability of the circuit.

10 Another object of the invention is to provide a device which may be used in connection with any high frequency circuit, such as an amplifier circuit or oscillating circuit, for example, to improve the operating characteristics of the circuit.

15 A tuned circuit will resonate to a frequency dependent upon the value of the inductance, capacity and resistance in the circuit. With an increase in either inductance or capacity, the resonance point of the circuit will be changed to 20 a lower frequency, and vice versa. In order to provide a circuit which may be tuned at a very high frequency, it is, therefore, necessary to make the values of inductance and capacity correspondingly small.

25 In connection with oscillators a "tank" circuit is frequently employed. Such a circuit may be roughly defined as a resonant circuit in which the ratio of capacity to inductance is relatively large. The circuit then has a "flywheel" effect, 30 that is, it has large circulating currents which tend to stabilize the frequency of the oscillator. To obtain the maximum benefit from such a circuit it is important to make the resistance of the circuit as low as possible as this increases the 35 sharpness of resonance and permits larger circulating currents to flow.

A feature of this invention is the particular shape and construction of a device which may be used as a tank circuit for high frequencies, 40 and which will have a particularly high capacity relative to its inductance for the frequency at which it is resonant, and have a particularly low value of resistance at this frequency.

In the drawing,

45 Fig. 1 is an end view of one species of the invention;

Fig. 2 is a side view of the device shown in Fig. 1;

Fig. 3 is a side view of another species of the 50 invention; and

Figs. 4, 5 and 6 are phantom views of additional species of the invention.

In Figs. 1 and 2, a metallic tube 1 has mounted thereon two metallic caps 2 and 3 having extended rims 4. The entire structure may be of

copper, for example. One or both of the caps may be adjustable so that the distance between rims 4 may be varied for tuning. When such a device is used as a resonant or tank circuit in high frequency circuits such as that of an oscillator, the tube 1 acts as an inductance while a capacity is formed between the rims 4. The inductance of the tube 1 is very low while the capacity between the rims 4 is relatively very high. There is apparently very little inductance in the circuit outside of that of the tube 1. The tube 1 and the caps have, of course, an extremely low value of resistance so that all of the conditions named above for a tank circuit are met.

10 A device such as that shown in Figs. 1 and 2, as well as the devices shown in any of the other figures, may be used in a circuit such as that shown in United States Patent No. 1,828,706 issued October 20, 1931, to Geoffrey G. Krusesi and me. In the circuits shown in that patent, this device could be used to replace the resonant circuits 17. Leads to the device could be connected, for example, to adjacent points on opposing rims 4, or to the ends of tube 1. If it is desired to connect the leads across only a portion of the inductance of the tank circuit, holes, as 12, 13, Fig. 2, may be made through the caps 2 and 3, and the leads run through these holes and connected to the tube 1. These leads need not interfere with the adjustment of the caps 2 and 3 as the holes may be large enough to allow for any desired adjustment. Similar holes may be made in the devices shown in the other figures. In Fig. 3 they may be made in the cap 14, and in Figs. 4, 5 and 6 in the outer cylinder.

15 The devices shown in Figs. 3, 4 and 6 operate in the same manner as that shown in Figs. 1 and 2. In each case there is a tube 1 which supplies the inductance, and a pair of plates 4 which supply the capacity. In each case the capacity is variable. In Fig. 3 it is varied by moving the tube 1 axially. In Fig. 4 the tube 1 is in two sections and one of the plates 4 is attached to each section. The capacity may be varied by moving the upper section of tube 1 axially, or this section of the tube may be threaded in a bushing 6 and the capacity varied by rotating knob 5. In Fig. 6 one of the plates 4 is secured to an inner shaft 7 and the capacity may be varied by moving this shaft axially, or the shaft may be threaded in a bushing 8 and the capacity varied by rotating knob 9.

20 In Fig. 5 a tube 10 may be moved relatively to another tube 11 of larger diameter, so that the tube 10 slides inside the tube 11. The capaci-

ity is varied in this manner, as it exists between tubes 10 and 11.

Of course, additional structure may be provided in the case of any of the devices shown, in order to increase the capacity. In Figs. 2, 3, 4 and 6, for example, the rims or plates 4 may be made larger. In Fig. 5 additional concentric tubes might be provided at each end of the structure and these tubes might be interleaved to increase the capacity, and in Figs. 2, 3, 4 and 6 additional interleaving plates might be provided for the condenser shown.

The structure shown in all the figures is self-shielded. The devices of Figs. 4, 5 and 6 may be evacuated or put under pressure, as circumstances and operating characteristics indicate to be desirable.

A special advantage may be obtained with the device shown in Fig. 3 by mounting an electronic tube coaxially with tube 1 with its base adjacent the right-hand plate 4. A number of parallel leads from the plate of the electronic tube may then be run through holes in the right-hand plate 4 and connected to the inner plate 4. A lead from the grid may then be connected to the center of right-hand plate 4. The inductance formed by the plate and grid of the electronic tube will then be reduced to a minimum.

What is claimed is:

- 30 1. An electrical circuit comprising, as a composite unit, a metallic cylinder forming an inductance element of the circuit, and a pair of dome-shaped metallic devices mounted at opposite ends of said cylinder in electrical contact therewith and having surfaces extending towards one another, said surfaces having adjacent rims in spaced relation to form a capacity element of said circuit.
- 35 2. An electrical circuit comprising, as a composite unit, a metallic cylinder forming an inductance element, a pair of annular metallic plates adjacent to one another, surrounding said cylinder and forming a capacity element of said circuit, and a pair of conducting elements mounted on said cylinder and supporting said plates in spaced relation and having surfaces of low resistance electrically connecting the ends of said cylinder to said plates.
- 40 3. An electrical device comprising, as a composite unit, a conductive plate forming one electrode of a condenser, a conductive tube forming an inductance element of an electrical circuit and having said conductive plate mounted thereon at one end thereof in electrical contact therewith, a conductive cap mounted on said tube in adjustable spaced relation to said plate and surrounding said tube in electrical contact therewith and a conductive plate carried by said cap and positioned opposite and in spaced relation to said first mentioned plate and forming the other electrode of said condenser which cooperates with said inductance element to provide a closed oscillatory circuit.
- 45 4. The combination of an electrically conductive cylinder, an electrically conductive tube electrically connected to one end of the cylinder and extending thereto, a conductive plate at the inner end of said tube in electrical contact therewith, a second electrically conductive tube adjustably mounted at the other end of said cylinder in electrical contact therewith and extending thereto, and a second conductive plate at the inner end of said second tube and co-operating with the other said plate to form a condenser, said cylinder and said tubes constituting

inductance connected in series with said condenser to form a closed oscillatory circuit.

5. An electrical circuit comprising, as a composite unit, a tubular element of relatively low inductance, a capacity element of relatively high capacity comprising a pair of relatively movable spaced plates, tubular metallic members having substantially no resistance surrounding said tubular element and electrically connecting said elements in a closed oscillatory circuit and physically supporting said plates in spaced relation upon said tubular element, and means for connecting leads across a portion only of said inductance element, said tubular metallic members having openings therein for the passage of said leads.

6. An electrical circuit comprising, as a composite unit, a tubular inductance element, a capacity element comprising a pair of relatively movable spaced plates, and metallic members of substantially no resistance surrounding said tubular elements in engagement therewith and supported thereby and physically supporting said plates in said spaced relation whilst electrically connecting said elements in a closed oscillatory circuit.

7. An electrical circuit comprising, as a composite unit, a hollow conducting member forming an inductance element of said circuit, two conducting plates, and means comprising two members mounted in adjustable spaced relation on said conducting element and physically supporting said plates upon said conducting element with one plate adjacent but spaced from the other to form a capacity element of the circuit, and electrically connecting said inductance and said capacity elements in series to form a closed oscillatory circuit.

8. An electrical device comprising, as a composite unit, a conducting rod constituting an inductance element of an electrical circuit, and a pair of conducting members spaced along said rod and electrically connected to and physically supported by said rod at spaced points thereon, said pair of members forming a capacity element for cooperating with said inductance element to provide a closed oscillatory circuit.

9. A high frequency circuit comprising, as a composite unit, a conductive supporting rod, two conductive elements mounted in adjustable spaced relation upon and supported by said conductive supporting rod, plates carried by said elements and constituting the condenser electrodes and said conductive supporting rod constituting the inductance of the circuit, and said conductive elements surrounding and forming a shield for said conductive supporting rod.

10. An electrical device, according to claim 8, characterized in this, that one of said conductive members is a flat annular plate forming the rim of a dome-shaped metallic member having an opening in the top thereof through which said conductive supporting rod extends.

11. An electrical device, according to claim 8, wherein each of said capacity element members is formed by the rim of a dome-shaped metallic member in which holes are provided for the passage of connecting leads to said inductance element.

12. An electrical circuit comprising, as a composite unit, a pair of conducting plates in spaced relation forming a capacity element of the circuit, means constituting an inductance element of the circuit and comprising a conductive rod, a tubular member encircling said rod and phys-

- ically supported thereby and thereon, said tubular member supporting one of said plates intermediate the ends of said rod and electrically connecting it to said inductance element, and means 5 electrically connecting the other of said plates to said inductance element and serving mechanically to support said other plate thereon with the space therebetween being intermediate the ends of said rod and the distance between the plates 10 being adjustable by movement of the tubular member lengthwise of said rod whilst maintaining electrical contact therebetween.
13. An electrical circuit comprising, as a composite unit, a pair of conducting annular plates 15 in spaced relation forming a capacity element of the circuit, a tubular member carrying at one end thereof one of said plates, means constituting an inductance element of the circuit and comprising a conducting rod passing through and 20 physically supporting said tubular member by telescopic engagement therewith, and means for supporting the other of said annular plates on said rod in concentric relation thereto and in spaced relation to the said one plate.
- 25 14. A high frequency circuit comprising, as a composite unit, a pair of flat annular metallic members forming the electrodes of a capacity element of the circuit, a metallic rod concentrically disposed within said annular members and 30 forming an inductance element of the circuit, a conducting tubular member surrounding said rod and at one end adjustably engaging said rod so as to be supported thereby and thereon and carrying one of said annular members at the 35 other end thereof, and means for supporting the other annular member on said rod in spaced parallel relation to said one annular metallic member.
15. An electrical circuit comprising, as a composite unit, a hollow conducting element forming an inductance in said circuit, two conducting plates, and metallic members in encircling engagement with said element and physically supporting said plates upon said conducting element 45 with one plate adjacent the other to form a capacity element of the circuit, and electrically connecting said inductance and said capacity elements in series to form a closed oscillatory circuit.
16. A high frequency circuit comprising, as a composite unit, a conductive supporting rod, two tubular conducting elements mounted in spaced relation upon and supported by said conductive supporting rod, said elements being provided with adjacently positioned surfaces constituting the 55 capacity of said circuit and said conductive supporting rod constituting the inductance of the circuit, and said conductive elements forming a shield for said conductive supporting rod.
17. An electrical device comprising, as a composite unit, a conductive plate forming one electrode of a condenser, a conductive tube forming an inductance element of an electrical circuit and having said conductive plate mounted thereon at one end thereof in electrical contact therewith, a 60 dome shaped metallic member mounted on said tube in electrical contact therewith and in adjustable spaced relation to said plate, and a conductive rim for said member positioned opposite 65 and in spaced relation to said plate and forming the other electrode of said condenser which cooperates with said inductance element to provide a closed oscillatory circuit, the said adjustable spacing being effected by a movement of said member lengthwise of said tube.
18. An electrical circuit comprising, as a composite unit, a metallic rod forming an inductance element of the circuit, a pair of dome shaped metallic devices mounted in spaced relation on said rod in electrical contact therewith, and a plate carried by each device, said plates being positioned in opposing spaced relation to form electrodes of a capacity element of said circuit, and one of said devices being movable on said rod so as to vary the spacing of said plates, thereby to change the capacity of said capacity element.
19. An electrical circuit comprising, as a composite unit, a cylindrically shaped metallic member constituting an inductance element of said circuit, two metallic plates constituting the electrodes of a capacity element of said circuit, means mounted on said member at one end thereof supporting one of said plates and electrically connecting it to said member, and means adjustably mounted on said member at the other end thereof supporting the other of said plates in spaced relation to the said one plate and electrically connecting it to said member, whereby the spacing of said plates may be adjusted to vary the capacity of said capacity element.
20. An electrical circuit comprising a cylindrically shaped metallic member constituting an inductance element of said circuit, two metallic plates positioned intermediate the ends of said member and constituting the electrodes of a capacity element of said circuit, means mounted on said member at one end thereof supporting one of said plates and electrically connecting it to said member, and means mounted on said member at the other end thereof supporting the other of said plates in adjustable spaced relation to the said one plate and electrically connecting it to said member whereby the spacing of said plates may be adjusted to vary the capacity of said capacity element.
21. An electrical circuit comprising a cylindrically shaped metallic member constituting an inductance element of said circuit, two metallic plates constituting the electrodes of a capacity element of said circuit, means mounted on said member at one end thereof supporting one of said plates and electrically connecting it to said member, and means mounted on said member at the other end thereof in adjustable spaced relation to the said first mentioned means and supporting the other of said plates in adjustable spaced relation to the said one plate and electrically connecting it to said member whereby the space between said plates may be varied by movement of the second mentioned means along the length of said member to adjust the capacity of said capacity element.
